UNITED STATES PATENT OFFICE

92,591

DESIGN FOR MACARONI OR SIMILAR ARTICLE

Vincent De Palo, Brooklyn, N. Y.

Application May 1, 1934, Serial No. 51,615

Term of patent 7 years

To all whom it may concern:

Be it known that I, VINCENT DE PALO, a citizen of the United States, residing at Brooklyn, in the county of Kings and State of New York, have invented a new, original, and ornamental Design for Macaroni or Similar Article, of which the following is a specification, reference being had to the accompanying drawing, forming part thereof.

Figure 1 is a top plan view of macaroni or similar article, showing my new design.

Figure 2 is a side elevational view thereof, Figure 3 is an end view of the same, Figure 4 is another end view of the same, and Figure 5 is a transverse sectional view on the line 5—5 of Figure 2.

I claim:—

The ornamental design for macaroni or similar article, as shown.

VINCENT DE PALO.
